UNITED STATES PATENT OFFICE.

HENRY M. RANSOM, OF MOUNT BETHEL, PENNSYLVANIA.

TURBINE WATER-WHEEL.

1,319,177.

Specification of Letters Patent. Patented Oct. 21, 1919.

Application filed November 20, 1918. Serial No. 263,366.

To all whom it may concern:

Be it known that I, HENRY M. RANSOM, a citizen of the United States, residing at Mount Bethel, in the county of Northampton and State of Pennsylvania, have invented new and useful Improvements in Turbine Water-Wheels, of which the following is a specification.

This invention relates to new and useful improvements in turbine water wheels and the principal object of the invention is to provide a number of wheels, one located above the other and so constructed that the water leaving one wheel will react on the next one.

Another object of the invention is to reduce the number of movable parts to a minimum by connecting the wheels directly to the driving shaft by suitable gearing.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation with parts in section and parts broken away.

Fig. 2 is a horizontal section on line 2—2 of Fig. 1.

Fig. 3 is a like section on line 3—3 of Fig. 1.

Fig. 4 is a section on line 4—4 of Fig. 1.

Fig. 5 is a view of the modification.

As shown in these views I locate a casing 1 between the ends of the upper and lower portions of the flume or penstock 2. Flanges 2' are formed on the ends of these portions and said casing is made of greater diameter than the flume so as to rest between said flanges. The said casing and flanges are secured together by suitable bolts as indicated at 2". The casing receives a pair of water wheels, the upper one of which is in-

dicated by the numeral 3 and the lower one by the numeral 4. This lower wheel 4 has secured thereto a cylindrical axle 5 having a conical top 6 and a plate 7 secured to its bottom. The said wheel is provided with an annular recess 8 at its upper end in its internal wall which receives the reduced lower end 9' of the upper wheel 9. This upper wheel is provided with the hub 10 which fits over the axle 5. These wheels are provided with buckets 11 formed of curved plates and the buckets on one wheel are oppositely arranged in respect to those on the other wheel. The lower wheel is provided with a beveled gear 12 at its lower end while the upper wheel is provided with a like gear 13 at its upper end and above this gear is arranged a flange 14 which is located between the upper part of the casing and the flange 2' of the upper part of the flume. Suitable anti-friction devices may be located between these parts to reduce friction. As will be seen the cone shaped upper end of the cylindrical axle extends above the casing into the lower end of the upper part of the flume 80 and this end supports a cone shaped deflector 15 provided with the curved plates 16 forming curved channels for directing the water into the buckets of the first wheel. As will be noted the channels in the deflector will direct the water on to the buckets of the first wheel at substantially a right angle thereto while the water leaving the first wheel will strike the buckets of the second wheel at substantially a right angle. 90 The casing 1 at one side is provided with a flattened part 17 provided with a journal for the drive shaft 18. At its inner end this shaft is provided with a beveled gear 19 meshing with the bevels on the upper and lower wheels so that power is transmitted from said wheels to said shaft. This power may be transmitted to any suitable machinery by means of a belt engaging a pulley 20 or by any other suitable means.

The water flowing through the flume will strike the deflector which will force the water toward the sides of the flume and due to the inclination of the channels in said deflector said deflector will be rotated and the water will pass from said channel on to the buckets of the first wheel. The water acting on said buckets will revolve this wheel in an opposite direction to that of the deflector and this wheel will in turn discharge the water 110

on to the buckets of the lower wheel so that this wheel will travel in the same direction as the deflector. As the last wheel and the deflector are secured together these two parts will move as one. The formation of the buckets and channels will cause the water to follow a zigzag path through the apparatus. In order to have the upper and lower beveled gears move at the same rate 10 of speed the depth of the first wheel may be adjusted relative to the lower wheel to cause the water to move said wheel at the same rate of speed as the lower wheel.

In the modification shown in Fig. 5 a second pair of wheels 20 and 21 are located below the first pair and the axles 22 are each provided with a beveled gear 23 oppositely arranged with the outermost gears 15 engaging a gear 24 carried by the shaft 18'. 20 In other respects this construction is similar to that just described.

It is thought from the foregoing description that the advantages and novel features 25 of my invention will be readily apparent.

I desire it to be understood that I may make such changes in the construction and in the combination and arrangement of the several parts, provided that such changes fall within the scope of the appended claims. 25

Copies of this patent may be obtained for five cents each, by addressing the "Commissioner of Patents, Washington, D. C."

What I claim is:—

1. A device of the class described comprising a number of water wheels having buckets oppositely arranged so that one wheel will be rotated in a direction opposite to that of the next wheel, gears carried on the 35 periphery of each of said wheels, a shaft and a gear thereon meshing with said gears.

2. A device of the class described comprising a flume, a casing located in said flume, a number of turbine wheels in said 40 casing, a hub connected with one wheel and with which the other wheel engages, a flange on the upper wheel engaging the top of the casing, a shaft, and transmission means connecting said shaft with the wheels. 45

3. A device of the class described comprising a flume, a casing connected therewith, water wheels in said casing having their buckets oppositely disposed, a hub connected with one wheel and engaged by 50 the other wheel, and a deflector connected with the top of the hub and having channels therein for directing the water on to the buckets of the first wheel at an angle thereto. 55

In testimony whereof I affix my signature.

HENRY M. RANSOM.
